ELECTRIC-IMPULSE TIME INSTRUMENT

Stanley Marsh Kenerson, Springfield, Mass., assignor to The Standard Electric Time Company, Springfield, Mass., a corporation

Application January 7, 1935, Serial No. 690

7 Claims. (Cl. 58—26)

This invention relates to improvements in electric-impulse time instruments.

One object of this invention is to provide an improved impulse clock having more silent operation.

Another object of this invention is to provide an impulse clock having an improved construction for more quickly and more precisely performing the resetting operation of the clock.

Another object of this invention is to provide an improved impulse clock formed of simple elements readily manufactured and readily assembled to produce an attractive, durable, efficient device at minimum cost.

With the above and other objects in view, this invention includes all improvements over the prior art which are disclosed in this application.

In the accompanying drawings, in which one way of carrying out the invention is shown for illustrative purposes:

Fig. 1 is a rear elevation of an impulse-clock movement made in accordance with this invention;

Fig. 2 is a vertical sectional view on line 2—2 of Fig. 4;

Fig. 3 is a vertical sectional view on line 3—3 of Fig. 4;

Fig. 4 is an edge elevation of the movement from the right of Fig. 1;

Fig. 5 is an enlarged sectional view on the line 5—5 of Fig. 3;

Fig. 6 is an enlarged fragmental view of the lower portion of Fig. 4, with the clutch-elements in unclutched position;

Fig. 7 is an enlarged sectional view on the line 7—7 of Fig. 2; and

Fig. 8 is an enlarged view of the upper portion of Fig. 1, with the rear movement-plate eliminated, but illustrating the positional relation of certain elements which are actually mounted on the rear of the rear movement-plate.

The present embodiment discloses improvements upon the impulse clock disclosed in my patent, No. 1,957,543, granted May 8, 1934.

In the description and claims, the various parts are identified by specific names for convenience, but they are intended to be as generic in their application as the prior art will permit.

Referring to the drawings, front and rear movement-plates 10 and 11 are secured together in spaced relation by two upper pillars 12 and two lower pillars 13. Each pillar consists of a spacing-element 14 and two screws 15 for clamping the movement-plates 10 and 11 against the spacing-element.

An hour-sleeve 16 is journaled for rotation in a hole 17 in the recessed gear-housing portion 18 of the front movement-plate 10. A minute-arbor or shaft 19 is journaled at the front end in the hour-sleeve 16 and in the hole 20 in the rear movement-plate 11. The minute-arbor 19, which ordinarily carries a minute-hand, has driving relation with the hour-sleeve 16, which ordinarily carries the hour-hand, by means of any suitable reduction-gearing which causes the hour-sleeve to rotate at one-twelfth the speed of the minute-arbor. Such reduction-gearing may include gears such as 21 and 22.

A clutch-element 23 and a weighted arm 24 are fixedly secured upon the minute-shaft 19 in any suitable way. In the construction illustrated in the drawings, the weighted arm 24 consists of a weight 25 secured by a screw 26 engaging in a threaded hole in a lug or arm 27 integral with a washer-like portion 28. The clutch-element 23 and weighted arm 24 are fixedly secured to the minute-shaft 19 in any desired way. In the drawings, these parts are shown fixed to the minute-shaft 19 by means of a pin 29, which forces the concave washer 30 heavily against the washer-portion 28, which latter forces the hub 31 of the clutch-element 23 heavily against the enlarged integral portion 32 of the minute-shaft 19, to thus frictionally but firmly secure the parts described, together. One end of the pin 29, it will be noted, engages between spaced-apart upstruck lug-portions 33 of the washer 30.

A second clutch-element 34 is mounted for free rotation upon the enlarged portion 32 of the minute-shaft, and has an annular groove 35 in its hub 36, in which groove ride the opposite fingers 37 of a clutch-arm or fork 38 having oppositely-extending pivot-portions 39 freely journaled in apertures 40 of the lower spacing-elements 14. An extension 41 of the clutch-fork is engaged by a leaf-spring 42 to normally urge the clutch-teeth 44 of clutch-element 34 into engagement with the clutch-teeth 43 of clutch-element 23.

In the form of the invention illustrated in the drawings, the clutch-element 34 has ratchet-teeth 45 formed around its periphery, thus constituting the member 34 a combined clutch-element and ratchet-wheel. A pawl-shaft or arbor 46 is mounted at its opposite ends on the cone-bearings 47 and 50. One of these cone-bearings 47 is formed on a screw 48, which threadedly engages in front movement-plate 10 and is held locked thereto by lock-nut 49. The other cone-bearing 50 is carried by a leaf-spring 51 secured

by screws 52 to the rear movement-plate 11. The hub 53 is secured in any suitable way as by screws 54, to the pawl-shaft 46, and in turn has secured to itself an arm 55 extending in opposite directions from the pawl-shaft. The arm 55 has fixed thereto studs 56 and 57, which respectively pivotally carry a pair of pawl-arms or pawls 58 and 59, the pawl-ends 60 and 61 of which are adapted to engage the ratchet-teeth 45 of the ratchet-wheel. 10 Fixedly secured to the pawl-shaft 46 is a limit-arm 62 having limit-portions 63 and 64 at its opposite ends, adapted to respectively engage sound-deadening elements or washers 65 and 66, secured on the rear of the rear movement-plate 11 by means of screws 67 and 68. The sound-deadening elements 65 and 66 may be of any suitable soft material such, for example, as rubber, and are preferably formed with the screw-receiving hole eccentrically therein, as illustrated, so that 15 by rotating the members 65 and 66 before tightening the screws, the sound-deadening elements can each be adjusted to stop the limit-portions 63 and 64 of the limit-arm 62 at desired adjusted positions. This permits of having the pawls 58 and 59 accurately move the minute-arbor, so that the minute-hand, ordinarily carried thereon, will accurately stop at the minute indications upon the clock (not shown). The spring 69 normally yieldably holds the limit-portion 64 in engagement with the limit-washer 66. 20

Also fixedly secured on the pawl-shaft 46 is an armature 70 having oppositely-extending portions 71 and 72 respectively in position to be attracted by the offset magnetic poles 73 and 74 of an electromagnet 75, which latter is secured to the inside of the rear movement-plate 11 by screws 76, as shown.

A pair of electromagnets 77 and 78 are secured to the inside lower part of the rear movement-plate 11 in any suitable way, as by screws 79 and 80. The electromagnets 77 and 78 have pole-pieces 81, 82 and 83, 84 (Fig. 2). The adjacent pole-pieces 81 and 83 have their upper ends V-shaped at 85 and 86 and adjacent each other and 45 adjacent the downwardly-pointing V-shaped nose 87 of the weight 25 of the weighted arm 24.

The clutch-fork or lever 38 has downwardly-dependant extensions 88 to which is secured in any suitable way, an armature 89 which extends 50 across from pole-piece 82 of electromagnet 77 to the pole-piece 84 of electromagnet 78. The armature 89 may be provided with projections 90 of non-magnetic material to prevent sticking of the armature 89 to the poles of the magnet. The 55 four feet or pads 91 fit in the sockets 92 of the front movement-plate and serve to cushion the pressure of the front movement-plate against the inside of the clock, to which it may be secured by screws passing through the feet 91 which are 60 preferably of soft material such, for example, as rubber.

When electric impulses are transmitted to the electromagnet 75 once per minute, as is usual in impulse or secondary clocks of the nature herein disclosed, the poles 73 and 74 pull the armature-portions 71 and 72 toward themselves and consequently cause the pawl 58 to be pushed downward in feeding movement to push on one of the pawl-teeth 45 to rotate the combined ratchet-wheel and clutch-element 34 a distance corresponding to approximately one-half the distance between two successive ratchet-teeth, while the pawl 58 is moved upward in idling direction, whereupon the limit-portion 63 of the limit-member 62 (Fig. 1) engages against the soft limit-

washer 65. Upon the electric circuit of electromagnet 75 becoming broken, the spring 69, pressing on the limit-portion 64 of the limit-bar 62, returns the limit-portion 64 to its normal position in engagement with the soft washer 66, and therefore rotates the pawl-shaft 46 back to its normal original position. In this reverse rotation under the influence of spring 69, the pawl 58 is moved upward in idling direction, while the pawl 59 is pushed downwardly and forwardly against a ratchet-tooth to partly rotate the ratchet-wheel a distance corresponding to the remainder of the distance between two successive ratchet-teeth. This oscillating action of the pawls takes place once each minute, to feed the ratchet-wheel 15 a distance corresponding to the distance between two successive ratchet-teeth. Each time the ratchet-wheel is moved forward a notch, the weighted arm 24 is made to travel a corresponding distance up away from its lowermost position 20 until it passes the top point of its rotation, whereupon it travels downward in the direction toward its original position.

In traveling downward toward its original position, the weighted arm 24 tends to rotate the ratchet-wheel 34 ahead of the pawls, which action if it were permitted to occur, would nullify the proper timekeeping characteristics of the clock. To prevent this happening, two limit-screws 93 and 94 screw-threadedly engage the rear of the front movement-plate 10 and carry eccentric bushings 95 and 96. By shifting these two bushings to suitably adjusted positions, and tightening the screws 93 and 94 to hold the bushings in desired positions of adjustment, the pawls 35 58 and 59 will be permitted their normal free movements in opposite endwise directions, for feeding the ratchet-wheel in its rotational direction, but will prevent the pawls 58 and 59 from being swung outwardly away from the ratchet-teeth by any rotational action, such as by the weight 25 tending to rotate the ratchet-wheel 34 ahead of the pawls.

At suitable intervals, such for example, as once an hour, say on the fifty-ninth minute of the hour, an electric impulse is sent from the master clock to the electromagnets 77 and 78, for the purpose of insuring that the clock is reset to accurate time. When this resetting impulse is sent through the electromagnets 77 and 78, the latter perform two operations. They attract the armature 89 to thus swing the clutch-fork 38 on its pivots 39 to slide the clutch-element and ratchet-wheel 34 longitudinally of the minute-arbor 19, and against the action of the spring 42 to unclutch the two clutch-members or elements, as illustrated in Fig. 6. In this unclutched position, which is held for a suitable interval of time, the weighted arm 24 is free to rotate and swing to its lowermost position, to which it is accurately and forcibly brought by the V-shaped magnetic poles 85 and 86 acting upon the corresponding V-shaped portion 87 of the weight 25 of the weighted arm 24, thus also rotating and accurately resetting the minute-arbor and minute-hand (not shown).

Upon breaking of the electric circuit of the electromagnets 77 and 78, the spring 42 forces the clutch-fork to swing the clutch-element 34 to bring its clutch-teeth into engagement with the corresponding clutch-teeth on the clutch-element 23. The number of the clutch-teeth 43 on the clutch-element 23 is equal, of course, to the number of teeth 44 on the clutch-member 34, and is also equal to the number of ratchet-teeth 45.

The front and rear movement-plates 10 and 11 are preferably made of molded composition material such, for example, as bakelite, which greatly aids in decreasing the noise of operation of the 5 clock. It will further be observed that the armature 18 does not at all contact with the poles 13 and 14 of the electromagnet 75, nor with any other metal part in any of its movements, the limit of the armature 18 and the pawl-shaft 46 10 being controlled by the soft, sound-deadening disks or bushings 65 and 66. While the parts of the device may be of various materials, the pawls 58 and 59 and the clutch-members 23 and 34 are 15 preferably made of molded composition such, for example, as bakelite.

The invention may be carried out in other specific ways than that herein set forth without departing from the spirit and essential characteristics of the invention, and the present embodiment is therefore to be considered in all respects 20 as illustrative and not restrictive, and all changes coming within the meaning and equivalency range of the appended claims are intended to be embraced therein.

25 I claim:

1. An electric-impulse time instrument construction including: a rotatable time-shaft; a first clutch-element fixedly secured to said time-shaft; a weighted arm fixedly secured to first 30 clutch-element; a second clutch-element adapted to be clutched to and unclutched from said first clutch-element by means of interengaging teeth on said clutch-elements, and adapted when unclutched to be rotatable relatively to said time-shaft and said first clutch-element; ratchet-wheel means having a number of ratchet-teeth corresponding to the number of teeth on each 35 clutch-element and rotatable with said second clutch-element; pawl-means adapted to rotate said ratchet-wheel means by a step-by-step movement and adapted to prevent rotation thereof except by feeding movement of said pawl-means; means normally holding said clutch-elements 40 clutched together; and means for unclutching said clutch-elements to permit said weighted arm to rotate to lowermost position and rotate said time-shaft to a corresponding position.

2. An electric-impulse time instrument construction including: a rotatable time-shaft; a first clutch-element fixedly secured to said time-shaft; a weighted arm fixedly secured to first 45 clutch-element; a second clutch-element adapted to be clutched to and unclutched from said first clutch-element, and adapted when unclutched to be rotatable relatively to said time-shaft and said first clutch-element; ratchet-wheel means rotatable with said second clutch-element and adapted to be rotated by a step-by-step movement; means normally holding said clutch-elements 50 clutched together; electromagnetic-means for unclutching said clutch-elements to permit said weighted arm to rotate to lowermost position and rotate said time-shaft to a corresponding position; and electromagnetic-means adapted to urge said weighted arm to rest at its lowermost position.

3. An electric-impulse time instrument construction including: a rotatable time-shaft; a 55 first clutch-element fixedly secured to said time-shaft; a weighted arm fixedly secured to first clutch-element; a second clutch-element adapted to be clutched to and unclutched from said first clutch-element, and adapted when unclutched to 60 be rotatable relatively to said time-shaft and

said first clutch-element; ratchet-wheel means rotatable with said second clutch-element and adapted to be rotated by a step-by-step movement; means normally holding said clutch-elements clutched together; means for unclutching 5 said clutch-elements to permit said weighted arm to rotate to lowermost position and rotate said time-shaft to a corresponding position; and a pair of electromagnets having a pair of poles adapted to urge said weighted arm to rest at its lowermost position.

4. An electric-impulse time instrument construction including: a rotatable time-shaft; a first clutch-element fixedly secured to said time-shaft; a weighted arm fixedly secured to first 15 clutch-element; a second clutch-element adapted to be clutched to and unclutched from said first clutch-element, and adapted when unclutched to be rotatable relatively to said time-shaft and said first clutch-element; ratchet-wheel means 20 rotatable with said second clutch-element and adapted to be rotated by a step-by-step movement; means normally holding said clutch-elements clutched together; electromagnetic-means for unclutching said clutch-elements to permit 25 said weighted arm to rotate to lowermost position and rotate said time-shaft to a corresponding position; and a pair of electromagnets having a pair of adjacent V-shaped poles adapted to urge said weighted arm to rest at its lowermost position, the portion of said weighted arm adjacent said poles also being V-shaped.

5. An electric-impulse time instrument construction including: front and rear movement-plates secured together; the front movement-plate being adapted to be secured to a support; a 35 time-shaft rotatably mounted in said movement-plates; ratchet-wheel means between said movement-plates and mounted on and adapted to rotate said time-shaft; oscillatable means including an oscillatable pawl-shaft, and pawls pivotally connected to the pawl-shaft and located between the movement-plates and adapted to actuate said ratchet-wheel means; and adjustable abutments mounted on the rear face of 40 the front movement-plate and adapted to be adjusted by access through an opening in the rear movement-plate.

6. An electric-impulse time instrument construction including: front and rear movement-plates secured together; the front movement-plate being adapted to be secured to a support; a time-shaft rotatably mounted in said movement-plates; ratchet-wheel means between said movement-plates and mounted on and adapted to rotate said time-shaft; oscillatable means including an oscillatable pawl-shaft, and pawls pivotally connected to the pawl-shaft and located between the movement-plates and adapted to actuate said ratchet-wheel means; adjustable 55 abutments mounted on the rear face of the front movement-plate and adapted to be adjusted by access through an opening in the rear movement-plate; a limit-arm secured to the pawl-shaft and located at the rear of the rear movement-plate; and adjustable limit-means mounted on the rear face of the rear movement-plate and adapted to limit the oscillation of the limit-arm and pawl-shaft.

7. An electric-impulse time instrument construction including: a rotatable time-shaft; ratchet-wheel means concentric with and adapted to rotate said time-shaft; an electromagnet having coil-means outside and spaced from an imaginary cylinder enclosing said ratchet-wheel 70 75

means and extending axially thereof, and having L-shape pole-pieces extending from said coil means toward said ratchet-wheel means, with the end-portions of said pole-pieces offset from each other and located outside said imaginary cylinder; an oscillatable pawl-shaft between said imaginary cylinder and said coil means and between the ends of said pole-pieces; pawl-means

connected to said pawl-shaft and adapted to rotate said ratchet-wheel means; and an armature secured to said pawl-shaft and having armature-5 portions extending oppositely from said pawl-shaft to locations adjacent corresponding pole-pieces.

STANLEY MARSH KENERSON.
